UNITED STATES PATENT OFFICE.

JOSEPH F. RIOUX, OF EDGEWOOD, RHODE ISLAND, ASSIGNOR TO A. A. GREENE AND CO.,
OF PROVIDENCE, RHODE ISLAND.

BRACELET.

1,203,271.

Specification of Letters Patent. Patented Oct. 31, 1916.

Application filed April 15, 1916. Serial No. 91,311.

To all whom it may concern:

Be it known that I, JOSEPH F. RIOUX, a citizen of the United States, residing at Edgewood, in the county of Providence and 5 State of Rhode Island, have invented a new and useful Improvement in Bracelets, of which the following is a specification.

This invention relates to certain new and useful improvements in bracelets and relates more particularly to bracelets of the 10 spring type.

The primary object of the invention is to provide a bracelet in which the units may be assembled into indefinite length to either 15 form an endless band or to form a chain length or piece in which the ends can be left blank to be connected to a watch or any other article.

Further, the invention aims to provide 20 new and novel means for enabling the springs to be easily and quickly connected in position, and to provide a chain of links which are assembled without the use of solder.

Still further, the invention aims to simplify the construction of bracelet links and 25 their assemblage, and incidentally involves other objects which will be later herein set forth and of themselves manifested in the 30 course of the following description.

In the drawings—Figure 1 is a fragmentary edge elevation of a chain of connected 35 links. Fig. 2 is a bottom plan view. Fig. 3 is a section on the line 3—3 of Fig. 2. Fig. 4 is a section on the line 4—4 of Fig. 3. Fig. 5 is a section on the line 5—5 of Fig. 3, and Fig. 6 is a detail perspective view of one of the links.

In proceeding in accordance with the present invention, each unit is formed of a box 40 1 and a back 2 having a channel 5 and side shoulders 3, the back being telescoped into the box as depicted in Fig. 4 and having its shoulders 3 engaged by the flanges or rolled over parts 4 of the box sides, which structure 45 effects securement of the backs to the boxes without the use of solder. The ends of the box are slotted at 6 to receive the connecting links 7 which latter have T-heads 8 engaged 50 in the respective boxes and have their opposite ends contracted and the contracted parts formed with hooks 9. The connecting links are tensioned by coil springs 10, which at one end receive the hooks 9 on their interiors and at their opposite ends abut the

adjacent ends of the boxes as depicted in Fig. 3, of the drawings. The hooks 9 thus act to hold the springs against movement in the boxes, *i. e.*, movement other than contractile and expansible, and during contraction act as guides for the springs in the collapsing movement of the spring coils, holding the latter from buckling action, in which function the hooks are assisted by the spring receiving channels 5. The channels 5 in addition contribute an ornamental value to the article and by virtue of the rounded contours thereof no sharp edges are present which latter have the tendency to cut or scrape against the wrist of the wearer in the 70 case of bracelets.

As depicted in Fig. 5 of the drawings the heads 8 are secured against movement by reason of being engaged by the side extensions 11 of the backs 2, which latter abut 75 the box bottom and are cut away to accommodate or receive the ends of heads 8 to impinge the latter against the adjacent ends of the boxes.

Having thus described my invention, what 80 I claim as new and desire to secure by Letters Patent—is

1. In a bracelet, or the like, a series of units each consisting of a box having slotted end walls and a back having a channel and having shoulders and side extensions the latter telescoping into the box and the side edges of the box being rolled over the back shoulders connecting links having T-heads on one end and hooks on their other ends, the links extending through the box slots and the back extensions having cut-outs which receive the head ends so that the latter will be held between the adjacent box ends and the back extensions, and coil 90 springs receiving the hooks on their interiors at one end and at their opposite ends abutting the adjacent box ends, the springs being disposed in the channels of the back.

2. In a chain structure, boxes having slotted ends, backs for the boxes connected thereto and having outwardly extending spring channels, connecting links for the boxes extending through the slots thereof, hooks on the other ends of the links, and coil 100 springs in the channel receiving the hooks on their interiors at one end and having their opposite ends abutting the adjacent ends of the boxes.

3. In a chain structure, a series of units, 110

- connecting links therefor, a single spring for each link disposed on one of the side faces of the link and between the side edges of said face, and means to guide the springs.
4. In a chain structure, units, connecting links therefor formed with central hooks extending on one side face thereof, and a single coil spring for each link to tension same, said springs receiving the hooks on their interiors.
5. In a chain structure, links consisting of boxes and backs therefor having side shoulders and extensions which latter telescope in the boxes, the side edges of the boxes being rolled over onto the shoulders of the backs, and spring tensioned connections between the links.
6. In a chain structure, units, connecting links therefor, one of the ends of the links having a hook disposed on a side face of the links, and a single spring for each link, said springs disposed on said side faces of the links and receiving the hooks on their interior.
7. In a chain structure, units each consisting of a box having slotted end walls, connecting links extending through the slots and having side extensions which engage the end walls beyond the slots, springs tensioning the links, and backs having side extensions which engage in the boxes and are cut away to receive the link side extensions whereby to hold the link side extensions be-

tween the box end wall and the side extensions of the back.

8. In a chain structure, units each consisting of a box, backs having side extensions which are received within the box and abut the box bottom, shoulders on the back extensions, said back having a channel extending outwardly from and arranged between the shoulders, the box side edge portions being extended inwardly and engaged over the back shoulders, and spring tensioned links connecting the units.

9. In a chain structure, units each including a box and a back, the back having a channel bowed outwardly therefrom and projecting out from the box, the box having its sides extended inwardly to engage on opposite sides of the back channel, and spring tensioned links connecting the units.

10. In a chain structure, units including boxes of angular cross-section and backs connected to the boxes and having rounded wrist engaging parts which extend outwardly from the back sides of the boxes, and spring tensioned connecting links for the units.

In testimony whereof I have signed my name to this specification in the presence of two subscribing witnesses.

JOSEPH F. RIOUX.
